UNITED STATES PATENT OFFICE.

HENRY SWARTESLANDER, OF OIL CITY, PENNSYLVANIA.

OIL-HEATER.

1,082,370.

Specification of Letters Patent.

Patented Dec. 23, 1913.

Application filed March 21, 1912. Serial No. 685,306.

To all whom it may concern:

Be it known that I, HENRY SWARTESLANDER, a citizen of the United States, residing at Oil City, in the county of Venango and State of Pennsylvania, have invented certain new and useful Improvements in Oil-Heaters; and I do declare the following to be a full, clear, and exact description of the invention, such as will enable others skilled in the art to which it appertains to make and use the same.

This invention relates to mineral oils, and more especially to the utilization of the gases arising therefrom; and the object of the same is to make use of such gases to heat the crude oil and thereby both cause the oil to give off a gas and lighten the oil when it is cold or thick and cause the water therein to precipitate.

These objects are accomplished by treating the raw product in the manner and by the apparatus hereinafter described and claimed, and diagrammatically illustrated in the drawing which shows an elevation of the apparatus I have successfully employed for this purpose.

In the drawing the numeral 1 designates a large tank for containing the crude petroleum as it comes from the well, when ordinarily it includes a mixture of oil and water. In summer time or when the weather is not too cold this water, being heavier than the oil, immediately settles to the bottom of the tank and may be drawn off from beneath the oil through one or more of the cocks 2 with which the tank is provided, the level of the water being visible through a sight gage 3, although any means for ascertaining such level and drawing off the water and oil may be employed. In cold weather, however, the oil thickens and the water remains in solution in it; and with some grades of oil the water and other extraneous matter remain in solution through all changes of the weather although it may be precipitated by heating the oil to a temperature of from 60° to 80° F., the exact point depending on the character of the oil, the foreign matters therein, and other conditions. It is necessary to free the oil of its most serious impurities before it is commercially fit for use, and my present invention is intended to perform this service by making use of the gas which is generated when the crude oil is heated.

In carrying out the process I provide a

pipe 4 which extends from a rather low point in the tank to a coil 6 located within an oven 7 which may be of brick or stone and will have a suitable air inlet controlled by a damper 8 and a proper flue 9 for the escape of the products of combustion which, in fact, may be utilized for purposes not necessary to mention. To the other end of the coil is connected a pipe 10 which extends back into the tank at a point 12 somewhat remote from the inlet end 13 of the pipe 4. Said pipes contain cocks 5 and 11 respectively, and these pipes should be substantially horizontal so that their entire length as well as all of the coils within the burner 70 will stand below the lowest level of the oil within the tank. The construction is such that when a fire is built in the oven beneath the coil, the crude oil therein is heated, and rises, and flows through the pipe 10 back into the tank 1 at the point 12 to replace the oil flowing out of the tank at the point 13, and a constant circulation is maintained in a manner which will be clear.

Let into the two pipes 4 and 10, and preferably within the oven, are two T-joints 14 and 15, from which upright pipes 16 and 17 respectively extend upward through the top of the oven and to a considerable height above it and above the highest possible level of the oil in the tank 1 as shown; there they are joined as at 18, and above this point a single pipe 167 extends into a reservoir 19 which is by preference disposed entirely above the top of the tank 1 so that by no possibility may oil gather within the reservoir. From the top of the reservoir leads a pipe 20 which is carried again downward (preferably passing through a regulator as indicated at 21) and to any suitable type of burner 22 which is located within the base of the oven beneath the coil 6. The initial heating of the latter will doubtless be effected by means of a small fire built below the coil, and the heating of the coil, the adjacent ends of the pipes 4, 10, 16 and 17, and the two T-joints 14 and 15, will cause the crude oil therein to throw off gas which naturally rises through the upright pipes 16 and 17 and accumulates within the reservoir 19. Furthermore the heat from the fire heats the burner 22, and the gas flowing thereinto, so that very soon the burning gas takes the place of the temporary fire which latter burns out, and thereafter the gas automatically thrown off by the heating of the

oil is utilized to continue heating the oil and therefore to replenish the gas as fast as it is consumed. Meanwhile the operator will keep watch of the condition of the oil within the tank and decant the impurities from time to time until it is sufficiently purified or refined to no longer need the action of the process to which it has been subjected, and then one or both cocks 5 and 11 will be closed, the flow of gas to the burner cut off as by means of a cock 25 with which its supply pipe is provided, and the apparatus connected with another tank or this tank emptied and supplied with another charge of crude petroleum so that the process may be repeated.

I emphasize the fact that the illustration herewith is not only diagrammatic but also susceptible of considerable modification and variation without departing from the essential principle involved.

I have suggested above that a regulator 21 might be inserted in the pipe 20 between the reservoir 19 and the burner 22. In some cases this might be entirely omitted, and the type of reservoir employed is not important. Its purpose would be to regulate the pressure of the gas flowing to the burner, and possibly also to regulate its volume although this might be done by the cock 25. In any event, the oil passes along one pipe, through the burner, and back in the other pipe, while the gas (either that thrown off

naturally or that thrown off by reason of the heat) rises through the pipes 16 and 17 which extend above the level of the oil in the tank, and finally accumulates within the reservoir. From the latter it is drawn as needed and fed to the burner, where it is burned to heat the coil. Thus it will be seen that this device burns gas generated naturally or by heat, but it does not burn the oil or the vapor therefrom, and therefore none of the oil is wasted.

What is claimed as new is:

The herein described apparatus for heating crude oil, the same consisting of a tank, a coil, pipes connecting the coil with the tank and standing throughout their length below the lowest level of the oil in the tank, an oven inclosing the coil, a burner therein beneath such coil, T-couplings within said pipes inside the oven and adjacent the coil, gas pipes leading upward from said couplings through the top of the oven, a gas reservoir located entirely above the level of the tank and with which these pipes are connected, and a gas feed pipe leading from the reservoir to the burner.

In testimony whereof I have hereunto set my hand in presence of two subscribing witnesses.

HENRY SWARTESLANDER.
